UNITED STATES PATENT OFFICE.

JOHN EADY, OF FIFE LAKE, MICHIGAN.

SNOWPLOW.

Application filed October 3, 1924. Serial No. 741,378.

To all whom it may concern:

Be it known that JOHN EADY, a citizen of the United States, residing at Fife Lake, in the county of Grand Traverse and State of Michigan, has invented certain new and useful Improvements in Snowplows, of which the following is a specification.

This invention relates to snow plows generally and particularly to plows for removing snow from railway tracks and among the various objects thereof may be mentioned the following as prominent ones:

To provide a snow plow for railways with means for vertically adjusting the forward receiving end thereof with relation to the ground or snow surface;

To provide a snow plow with a forwardly and downwardly inclined body with side boards adjustable for the purpose of delivering snow onto a flat-car in the rear of and coupled therewith or for delivering the snow to the sides of the trackway;

To provide novel and simple means for operating, adjusting and supporting the mechanisms and elements for carrying out these objects.

With these and other objects in view, my invention consists in the novel features of construction, combination and arrangement 30 of parts as will be hereinafter referred to and more particularly pointed out in the specification and claims.

Referring to the drawings wherein for the purpose of illustration is shown the preferred embodiment of my invention,—

Figure 1 is a side elevation of the snow plow;

Figure 2 is a substantially central longitudinal section;

Figure 3 is a plan view showing alternative position of the side boards;

Figure 4 is a bottom plan view of the machine;

Figure 5 is a transverse section on the line 5—5 of Figure 1;

Figure 6 is an enlarged detail bottom plan view of the stanchion locking means; and

Figure 7 is an enlarged detail section thereof.

Referring specifically to the drawings by numerals of reference, 2 designates a railway track and 4, in dotted outline a flat-car to which my snow plow may be coupled as a one source of propulsion.

The snow plow forming the subject of this invention comprises a forwardly and

downwardly inclined frame 5, the side and end sills of which are shown respectively at 6 and 8, said frame supporting the body 10 in the usual or any approved manner. 60 The frame 5 is supported to the rear of its longitudinal center by means of pairs of standards 12 and 14, the former being relatively shorter than the latter and each being bolted to the under face of the side 65 sills at their upper ends, while their lower ends which may be formed into a unitary structure as at 15 are bolted upon the upper face of journal blocks 16 in which is journaled the rear axle 18 carrying the track 70 wheels 19. To lend greater stability to the structure, I provide a pair of crossed struts or tie bars 20 connected at their ends respectively with the under face of the side sills and the journal blocks 16. Supported 75 at its ends respectively in the forward transverse sill 8 and a hanger 21 depending from and supported by the rear portions of the side sills 6, is a centrally and longitudinally disposed draft or pusher bar, 22, the rear 80 extremity being provided with a coupler 24 for connection to the draw bar 25 of the flat-car 4.

In practice, the rear delivery end of the plow body is disposed over the adjacent 85 end of the flat-car as shown in Figure 1, and as the snow is gathered by the knife-edged forward extension 26 of the metal floor, it is moved upwardly and rearwardly between the side boards 28 and eventually 90 deposited upon the flat-car.

Under certain conditions it is desirous that the snow be delivered to the sides of the plow instead of depositing it upon the flat-car, and to this end, I mount each side board 95 at its rear end upon vertical pivots as shown at 29 in any suitable manner, whereby said side board may be swung inwardly as shown by dotted lines in Figure 3 so that they present in plan, a V or triangle the apex or cutting point 30 of which is forwardly directed to cause the snow gathered by the forward extension to be moved laterally and off the side of the car.

To provide means for maintaining the side 100 boards 28 in either of the positions described or as shown respectively in full and dotted lines in Figure 3, there are arranged in pairs upon the opposite sides of the car and adjacent the center respectively, stanchions 110 32 with locking devices for supporting them in fixed position, and since the stanchions and

the locking means incident to each are of the same construction, only one need be described.

Each stanchion 32 comprises a metallic bar 5 having a hooked upper end 33 for straddling the upper edge of the side board and preventing lateral displacement thereof, the lower end passing through an opening 34 in the car floor and being provided with a pair of lateral diametrically disposed lugs 43. Clamped to the under side of the car floor and provided with an opening 35 registering with that in the car floor is a casting 36 provided with an annular flange 38, the latter having an arcuate slot 39. Arranged to oscillate in a horizontal plane within the annular flange 38, is a locking plate or disk 40, having a central bayonet opening 41 in registry with the openings 34 and 35 in the car floor and casting respectively, said disk being provided with a radial operating arm 45 which is movable in the arcuate slot 39. It is obvious from reference to Figures 6 and 7 that when the stanchion has its lower end projected through the several registering openings 34, 35 and 41, and the disk 40 turned through an angle of 90 degrees, the lugs 43 will take under the lower face of the said disk and be thus locked against removal.

Under certain conditions, as for instance in transporting the plow from place to place, or where it is desired to regulate the vertical elevation of the forward end thereof, it is necessary to provide means for effecting the raising or lowering of said forward end, and for this purpose, I journal the forward axle 48 in the lower ends of the arms 50 of an inverted U-shaped link or standard, the horizontal transverse member 51 of which passes through and is suitably journaled in the forward portions of the side sills 6. The vertical adjustment is affected by swinging the link and with it, the front wheels 66 on the axis of the transverse bar 51, and to this end, I provide an actuating rod 54, the forward bifurcated ends of which are provided with eyes 55 through which passes the front axle 48, while the rear end is pivotally connected as at 56 with the crank arm 59 of a crank shaft 60 journaled transversely below the floor of the car body in the standards 14. The crank shaft may be operated either by a handle 61

or through the medium of a cable or rope 55 62, which is connected with the free end 63 of the crank and which passes over a pulley 64 to a point convenient of operation by the person on the flat-car or motor car. It is quite obvious that where it is desired to deliver the snow to one side of the plow only, one of the side boards may be maintained in parallel relation with the side of the floor while the other is moved obliquely across the floor as shown by dotted lines in Fig. 3. 65 Further any suitable and obvious arrangement of pulley may be used to reverse the operation of the crank shaft 60.

From the foregoing description of the construction of my improved apparatus, it 70 will be seen that I have provided a simple, inexpensive and efficient means for carrying out the objects of the invention, and while I have particularly described the elements 75 best adapted to perform the functions set forth, it is obvious that various changes in form, proportion, and in the minor details of construction may be resorted to, without departing from the spirit or sacrificing any 80 of the principles of the invention.

What I claim as new and desire to protect by Letters Patent is:—

1. A snow plow comprising a body, a wheel mounted standard located under the rear portion of the body, a wheel mounted standard located under the forward portion of the body, the said body being disposed in an inclined position with relation to both standards, means for varying the angle of inclination of the body with relation to the standards, and a push-bar connected with the body at a point between the standards. 85

2. A snow plow comprising a body, a wheel mounted standard located under the rear thereof, a wheel mounted standard located under the forward portion thereof, the body being disposed at an angle with relation to both of the standards, means for varying the angle of inclination of the body with relation to both of the standards, and a push-bar connected with the body at a point between the standards and at a point nearer the forward standard than the rear standards. 90

— In testimony whereof I affix my signature. 105

JOHN EADY.
